UNITED STATES PATENT OFFICE.

WALTER VANDER HEYDEN WILLSON, OF TROY, ASSIGNOR OF ONE-HALF TO
HERBERT F. ASHTON, OF WEST TROY, NEW YORK.

SAND-BOX FOR CARS.

SPECIFICATION forming part of Letters Patent No. 444,034, dated January 6, 1891.

Application filed September 25, 1890. Serial No. 366,093. (No model.)

To all whom it may concern:

Be it known that I, WALTER VANDER HEYDEN WILLSON, of the city of Troy, county of Rensselaer, and State of New York, have invented a new and useful Improvement in Sand-Boxes for Cars, and of which the following is a specification.

My invention relates to improvements upon that class of apparatus which is used to supply sand to the tracks of electro-motor and other cars when the tracks are slippery, so as to increase the traction capacity of the wheels.

My invention consists (as will be more fully detailed hereinafter in connection with its illustration) in the combination, with a hopper or box provided with a discharge-passage at its lower end and adapted to receive and contain sand, of a wheel having a shaft with bearings on which to turn within said box or hopper and provided with buckets, with said wheel so arranged with relation to the interior of the box or hopper that the outer edge of the buckets will be so close to the sides thereof as to prevent sand from passing through the opening in the bottom of the hopper when the wheel is at rest, and when the latter is turned that each bucket will deliver to the bottom opening of the hopper the sand which it holds, so as to have it pass therefrom into a chute leading to a point over the track.

Accompanying this specification to form a part of it there are two plates of drawings containing four figures illustrating my invention, with the same designation of parts by letter-reference used in all of them.

Of the illustrations, Figure 1 is a top view of the apparatus containing my invention, with the latter shown as applied to the under side of a car with the floor of the latter and that of one of its end platforms shown as removed. Fig. 2 is a section taken longitudinally through the car-floor and one of the end platforms, showing in elevation one of my sand-boxes located within and at one end of the car where it would be beneath one of the car-seats were the latter shown. This view shows a means for operating the sand-wheels. Fig. 3 shows a section taken on the line $\alpha\alpha$ of Fig.

1, with the parts increased in size. Fig. 4 shows a modification in which one sand-box is used beneath the car-bottom, said box being provided with branch chutes leading from the main discharge at the hopper-bottom to each of the rails of the track, with the car-bottom shown in cross-section, the hopper shown in central longitudinal section, with the wheels and gears operating the shaft of the latter shown in elevation.

The several parts of the mechanism thus illustrated are designated by letter reference and the function of the parts is described as follows:

The letter B designates the car-bottom, C the car-wheels, and T the track.

The letter H designates the hopper, having a bottom opening O, as shown at Fig. 3.

The letter W designates the sand-wheels, of which, as shown at Fig. 2, there are two upon one shaft S^2 to be operated connectedly. These wheels are each made with buckets B^2 , and each of these sand-wheels is arranged within a hopper, so that the ends of the bucket-arms a thereof will, as the wheel revolves, pass close to the inner wall E of the hopper H, so that when the wheel is at rest no sand will pass down between the ends of the bracket-arms and the hopper-bottom, but so that when the wheel is turned each of the brackets upon the wheel when going down will discharge the sand they hold into the opening O, to pass through the latter to the chute C^2 , when the sand is distributed on the track. To insure the delivery of the sand in measured quantities, the lower part of the hopper is rounded out at E semicircularly to correspond to the traverse made by the outer edges of the radially-arranged buckets, and so as to leave just enough space between the edges of the buckets and the bottom E for the latter to pass, but so as to prevent the sand from passing between the bucket-arms and the rounded surface of the hopper. Where a free passage of the sand occurs, as when a valve is opened at the bottom, the amount of sand passing down is irregular, and often the box becomes exhausted of its contents before the trip of a car is completed from such an irregular means of delivery, but by using buckets that fill

with and empty the sand as the sand-wheel is rotated the measure of sand delivered is regulated.

- To operate the wheel any well-known means 5 may be employed, that shown being a crank A on the vertical shaft S, having a beveled gear G' on its lower end, where, beneath the end platform - floor F, this beveled gear-wheel G' meshes into another beveled gear-wheel G² on the end of the shaft S³ with the other end of the latter opposite to that on which the gear-wheel G² is located, being constructed with a worm-gear W², which meshes into a gear-wheel G⁴ on the shaft S².
- 15 In the modification shown at Fig. 4 the shaft S² of the sand-wheel W is operated by a beveled gear g' on the shaft m', and this gear-wheel meshes into a beveled gear-wheel g² on the shaft S³ to communicate motion to said sand-wheel. When one sand-wheel and hopper are used on the actuating-shaft S² and located centrally, as shown at Fig. 4, the hopper discharges the sand into two chutes C', one of which runs to each side of the car to 20 distribute sand to each of the rails forming the track. When it is desired to operate the mechanism thus described, the shaft S³ of the bucket-wheel is turned by the crank on the vertical shaft S, which, by means of the geared 25 connection the lower end of the latter makes with the shaft S³ and the worm-gear connection the latter shaft makes with the shaft S², on which one or two sets of like apparatus, as shown. As the wheel W is turned so as to revolve within the sand A² contained in the 30 hopper, the buckets become filled and are each emptied through the opening O as the buckets each pass over the latter, with the outer edges of the buckets closing against the interior 35 walls E of the hopper to prevent the escape of any sand from the hopper other than that delivered by the buckets, with the sand so set free by the latter passing into a chute to be dropped upon the track.
- 40 45 The sand-box and combined bucket-wheel thus illustrated can be applied to the bottom of the car, as shown at Fig. 1, or it can be arranged to have the hopper part project up into the car, as shown at Fig. 2, and in a position where the body of said hopper would be beneath one of the seats. The hopper is 45 preferably made of galvanized sheet-iron, and the buckets or the wheel are preferably made of sheet metal.
- 50 55 As the operation of the hopper made as described, in combination with a bucket-wheel arranged to be turned therein, would perform the same co-operative function whether the shaft of the bucket-wheel was operated by 55 the mechanism which I illustrate and describe or some other mechanism that would operate the wheel to turn in the hopper in

the same manner, hence I do not limit my invention of the combined hopper and wheel, as I illustrate and describe them to the particular means shown to operate said wheel. 65

I am aware that a sand-delivery box has been patented in which a rotating valve was arranged in the bottom of a hopper-opening and constructed to turn with a shaft below the latter, and so that when said valve was open the sand could run down in a free passage from the hopper to the chute, with the valve-shaft of this older device provided with a pinion that meshed into a pinion upon an 70 agitator-shaft, which latter was arranged within the hopper, the whole being operated by a rack that meshed into the pinion on the valve-shaft and by which, when the rack was reciprocated, the agitator and the valve were 75 reciprocatingly rotated with the valve when open, furnishing a free passage of the sand from the hopper to the chute. This device differs from mine in the fact that I use no valve to open and close an opening in the 80 bottom of the hopper.

Having thus described my invention, what I claim, and desire to secure by Letters Patent, is—

1. In an apparatus for distributing sand to 90 a car-track, the combination, with a hopper adapted to contain sand and constructed with a rounded-out bottom having a discharge-opening, of a wheel having perimetral buckets, with said wheel constructed to be rotated within said hopper and the rounded bottom thereof, and said buckets constructed to deliver sand to said bottom-opening when said wheel is rotated and to prevent the delivery of the sand through said opening when the 95 wheel is at rest, substantially as and for the purposes set forth.

2. In an apparatus for distributing sand to a car-track, the combination, with a hopper adapted to contain sand and provided with a rounded-out bottom provided with an opening and connected conveying-chute, of a sand-wheel having perimetral buckets, with said wheel constructed to be rotated within said hopper and the rounded bottom thereof, and said buckets constructed to deliver sand to said bottom-opening and chute when said wheel is rotated and to prevent the delivery of sand through said opening when the 105 wheel is at rest, substantially in the manner 110 as and for the purposes set forth.

Signed at Troy, New York, this 19th day of July, 1890, and in the presence of the two witnesses whose names are hereto written.

WALTER VANDER HEYDEN WILLSON.
